UNITED STATES PATENT OFFICE.

HAROLD D. REICHARD, OF AKRON, OHIO.

DESIGN FOR A TIRE TREAD.

Application filed June 17, 1922. Serial No. 2,726. Term of patent 14 years.

To all whom it may concern:

Be it known that I, HAROLD D. REICHARD, a citizen of the United States, residing at Akron, in the county of Summit and State of Ohio, have invented a new, original, and ornamental Design for Tire Treads, of which the following is a specification, reference being had to the accompanying drawings, forming a part thereof.

In the drawings Figure 1 is a top plan view of a portion of the tire tread.

Figure 2 is a cross section on the line 2—2 of Figure 1.

I claim:

The ornamental design for a tire tread as shown.

HAROLD D. REICHARD.
